UNITED STATES PATENT OFFICE

HUMBERT M. FENATI, OF NEW CASTLE, PENNSYLVANIA

METHOD OF MAKING BUILDING BRICKS

Application filed January 22, 1930. Serial No. 422,586.

My invention refers to the art of brick making and consists of an improvement in the method of making a rough face or tapestried brick.

3 The invention provides for the application to the surface or surfaces of the extruded clay column of a continuous brick machine, of a series of curved plowed lines or gutters, regularly spaced across the surface of the column 10 and of the resulting brick units.

In the drawings, showing the invention somewhat diagrammatically:

Fig. 1 is a perspective view illustrating the manner of imparting the desired surface lines 15 or grooves;

Fig. 2 is a similar view of one of the resulting bricks after severance from the column;

Fig. 3 is a view of the operation in side elevation;

20 Fig. 4 is a plan view of Fig. 3;

Fig. 5 is an end view of a severed brick;

Fig. 6 is a plan view of such brick.

In the manufacture of bricks and the like, a continuous column or bar 2 of plastic clay is 25 forced outwardly from the discharge nozzle 3 of a brick machine, of well known construction.

For the purpose of imparting a series of curving part circular score marks 4 of ragged 30 outline and gutter or groove form, I utilize a rotatable disk 5 suitably mounted by a driving shaft above the top surface of the column or blank 2 and inclined to the surface thereof, as in Fig. 3.

35 The lower side of disk 5 is provided with a series of annular spikes or pins 6 spaced radially in a plurality of series from the outer edge of the disk inwardly, as shown.

As the blank or bar 2 moves outwardly, the 40 wheel 5 is rotated, pins 6 sweeping around over and through the upper surface of the clay column, forming the continuous series of ragged, rough edge, irregular but regularly spaced curved lines or score marks 4.

45 One or both edges of bar 2 may be treated in the same manner by means of a similar disk 5a having similar pins 6a, the disk being similarly tilted or inclined to the surface of the bar, so that the pins engage only at the side where the disk is closest to the bar 2. By

such arrangement the pins beyond the center of either disk are elevated beyond the surface of the bar and do not cut into it, except at the other or lowered side of the disk.

The effect of such treatment is to impart a 55 continuous series of such curbed score marks across the face or faces of the bar, increasing in depth towards the middle thereof and decreasing in depth from the middle towards the other edge. 60

When it is cut or severed into the brick units, as by wire cutting, each severed brick is covered on its edge or end or ends with such plowed marks 4, as shown in Fig. 2. When the bricks are burned in the usual way, the 65 curved score marks give to the faces of the brick an attractive or ornamental appearance, greatly enhancing its value in an artistic and novel manner.

It will be understood that the rotatable 70 disks may be mounted by their drive shafts so as to be adjusted towards or from the surface of the bar or with variation of inclination, and otherwise provided with suitable driving gearing and other necessary mechanism, in order to effect the operation to the best advantage. 75

The speed of operation, spacing of the pins, number of annular rows, and other details of operative mechanism may be entirely within the control of the machine builder, and it will be understood that I do not limit the invention to any particular means for accomplishing the result. 80

What I claim is:—

1. In the manufacture of bricks, the method of surfacing the face of a moving bar of plastic clay consisting in plowing across it by annularly and vertically moving pins. 85

2. In the manufacture of bricks, the method of surfacing the face of a moving bar of plastic clay consisting in plowing across it by annularly and vertically moving pins moving in a non-parallel path. 90

3. In the manufacture of bricks, the method of surfacing the face of a moving bar of plastic clay consisting in rotating a series of pins over and through the face of the bar at varying depth in a non-parallel path. 95

4. In the manufacture of bricks, the method 100

od of surfacing the face of a moving bar of plastic clay consisting in rotating a series of scoring pins in an annular path at an incline to the face of the bar whereby the pins will score the bar at one side of their path of movement.

5. In the manufacture of bricks, the method of surfacing the face of a moving bar of plastic clay consisting in plowing across it at varying depths by annularly moving pins, and then severing the bar into brick units.

In testimony whereof I hereunto affix my signature.

HUMBERT M. FENATI.
